CLAIM

The ornamental design for a mobile terminal display with graphical user interface for a mobile game assistant, as shown and described.

DESCRIPTION

FIG. 1 is a front view of a mobile terminal display with graphical user interface for a mobile game assistant, showing a first embodiment of the new design;
FIG. 2 is a second embodiment thereof;
FIG. 3 is a third embodiment thereof; and,
FIG. 4 is a fourth embodiment thereof.

The broken line immediately adjacent to the outer edge perimeter of the graphical user interface shows a display screen, and forms no part of the claimed design.
